(57) **CLAIM**

The ornamental design for a storage bracket for accessories of cleaning appliance, as shown and described.

DESCRIPTION

1. Storage bracket for accessories of cleaning appliance
2. Storage bracket for accessories of cleaning appliance

1.1 : Front

1.2 : Back

1.3 : Left

1.4 : Right

1.5 : Top

1.6 : Bottom

1.7 : Perspective

1.8 : Perspective

1.9 : Perspective

2.1 : Front

2.2 : Back

2.3 : Left

2.4 : Right

2.5 : Top

2.6 : Bottom

2.7 : Perspective

2.8 : Perspective

2.9 : Perspective

1.1 is a front view of a first storage bracket for accessories of cleaning appliance, 1.2 is a back view thereof, 1.3 is a left

(Continued)

view thereof, **1.4** is a right view thereof, **1.5** is a top view thereof, **1.6** is a bottom view thereof, **1.7** to **1.9** are three perspective views thereof; **2.1** is a front view of a second storage bracket for accessories of cleaning appliance, **2.2** is a back view thereof, **2.3** is a left view thereof, **2.4** is a right view thereof, **2.5** is a top view thereof, **2.6** is a bottom view thereof, **2.7** to **2.9** are three perspective views thereof.
